UNITED STATES PATENT OFFICE.

CHRISTIAN FREDERICK SAUEREISEN, OF MILLVALE BOROUGH, PENNSYLVANIA.

DESIGN FOR A PAPER-WEIGHT.

40,583.

Specification for Design. Patented Mar. 22, 1910.

Application filed January 24, 1910. Serial No. 539,909. Term of patent 3½ years.

To all whom it may concern:

Be it known that I, CHRISTIAN FREDERICK SAUEREISEN, a resident of Millvale borough, in the county of Allegheny and State of Pennsylvania, have invented a new, original, and ornamental Design for Paper-Weights, of which the following is a specification, reference being had to the accompanying drawing, forming part thereof, in which—

Figure 1 is a perspective view of a paper-weight, showing my new design, and Fig. 2 is an end elevation thereof.

I claim—

The ornamental design for a paper-weight as shown.

CHRISTIAN FREDERICK SAUEREISEN.
